United States Patent [19]

Drinhaus

[11] Patent Number: Des. 365,995

[45] Date of Patent: **Jan. 9, 1996

[54] **RADAR CROSS SECTION MEASUREMENT PYLON TERMINATING DEVICE**

[75] Inventor: **Mark T. Drinhaus**, Quartz Hill, Calif.

[73] Assignee: **Lockheed Corporation**, Calabasas, Calif.

[**] Term: **14 Years**

[21] Appl. No.: **37,220**

[22] Filed: **Apr. 6, 1995**

[52] U.S. Cl. **D10/47**; D10/46; D10/103

[57] **CLAIM**

The ornamental design for radar cross section measurement pylon terminating device, as shown and described.

DESCRIPTION

FIG. 1 is a perspective view of the radar cross section measurement pylon terminating device;

FIG. 2 is a side view of the radar cross section measurement pylon terminating device;

FIG. 3 is a top view of the radar cross section measurement pylon terminating device;

FIG. 4 is a bottom view of the radar cross section measurement pylon terminating device;

FIG. 5 is a front view of the radar cross section measurement pylon terminating device;

FIG. 6 is a rear view of the radar cross section measurement pylon terminating device; and,

FIG. 7 is a partial cross-sectional view taken along line 7—7 of FIG. 4.
